UNITED STATES PATENT OFFICE.

WILLIAM J. PETERSON, OF MINOT, NORTH DAKOTA, ASSIGNOR OF ONE-HALF TO
OSCAR H. LARSON, OF MINNEAPOLIS, MINNESOTA.

COVER FOR TIMER WIRES.

Application filed April 3, 1922. Serial No. 549,182.

This invention relates to a cover for a timer wire assembly to prevent the wires from becoming short-circuited on account of the oil, water, and dirt which accumulates around the timer-shell and destroys the insulation on the timer wires.

An important object of the invention is to provide a cover of the character above specified which may be readily attached to the timer and which incloses the timer wires in such manner that the latter are shielded against deterioration and at the same time brought into electrical engagement with the timer.

15 A further object of the invention is to provide a device of the character above specified simple in construction, strong and which is believed may be manufactured at a reasonably low cost.

20 Various other objects and advantages of the invention will become apparent during the continuance of the following description.

In the drawing:

Figure 1 is a view of the proposed cover 25 in side elevation.

Figure 2 is a cross sectional view of the cover as taken on line 2—2 of Figure 1, and

Figure 3 is a central longitudinal section taken on line 3—3 of Figure 2.

30 This cover is formed as a flat rigid annular body comprising two fibre rings 10 and 11 respectively encircling the back portion of the timer, which is indicated by the dotted line structure 12 of Figure 2. These rings

35 are preferably held together with sealing wax and a suitable number of rivets 13, and are provided with an offset portion or throat 14 over which engages one end of a tapering funnel 15. This funnel is preferably

40 flattened on the opposite sides of its inner end and is secured to the ring by a rivet 16. To the outer end of the funnel is soldered or otherwise fastened a metallic flexible casing 17 thru which extends the

45 timer wires 18.

The terminal ends of wires 18 are adapted to be enclosed between rings 10 and 11, one of which is suitably grooved as shown at 19, terminate at their innermost ends adjacent

50 slots 20 which are arranged at relatively spaced points in the circumference of the rings. Projecting thru each slot is the U-shaped securing end of a contact member 21 which has a right-angle base fitted in a suit-

able cut-out 22 on the inside of the ring. 55 Each terminal is connected to the end of a wire 18 which conducts the current from the timer to the coil. When the rings are in place on the timer the U-shaped ends of terminals 21 engage over contact posts 23 of 60 the timer, being clamped in place by the binding nut 24.

The grooves 19 converge towards the throat portion of the cover at which point the wires enter between the rings. At this 65 point also, the entering wires may be taped to avoid a short-circuit on the funnel 15.

The cover may be coated with sealing wax 25 on the outside to prevent oil, water, dirt or grease from accumulating on the wire-ends 70 which are thereby protected from deterioration and so shielded in their connection with the timer as to avoid a short circuit by the accumulation of oil, water etc., as previously set forth, this coating 25 also aids in holding 75 the disks 11 and 12 in proper position and as already shown in Figs. 2 and 3, forms a casing for the cover extending from the funnel 15 around the same, which casing is of flat annular shape and is comparatively 80 thin. The flat contact members 21 have their inner ends conveniently disposed flat against the flat ring 11.

From the foregoing it is believed that the advantages and novel features of the invention will be readily understood and that further detail description is unnecessary.

What is claimed is:

1. A timer wire assembly and protective device comprising a pair of connected annular disks of insulating material adapted to fit in assembled relation over one side of the timer casing, one of said disks having circumferentially spaced slots therein and spaced grooves extending circumferentially 95 from said slots, respectively, to a portion of the edge of said disk, angle plates, each having one portion disposed in said slots, timer wires disposed in said grooves and permanently connected to said plates, said plates 100 each having another portion extending through said disk at right angles thereto and provided with U-shaped openings at their ends adapted to fit over the terminals on said timer casing when said disks are placed 105 thereon.

2. A timer wire assembly and protective device comprising a pair of connected annu-

lar disks of insulating material adapted to fit in connected relation over one side of the contact ring of the timer of a Ford or similar automobile, said disks having timer wires disposed therebetween in spaced relation and extending circumferentially thereof, circumferentially spaced terminals secured to the ends of said wires and having U-shaped clips projecting through and normal to one of said disks and adapted to embrace the terminals of the contact ring when the disks are placed thereon.

3. The structure set forth in claim 2, and a cover enclosing said disks and holding them in fixed relation.

4. The structure set forth in claim 2, said disks having alined laterally projecting portions between which said timer wires pass, and a funnel member enclosing said portions and adapted to have a wire containing conduit secured thereto whereby said wires are completely enclosed.

5. A cover or shield for a timer wire assembly comprising a pair of fiber rings fastened side by side and jointly offset to provide a throat portion, one of said rings having slots arranged at relatively spaced points in its circumference and being grooved to receive the terminal ends of the timer wires, said grooves respectively extending from the throat portion to one of the said slots, a funnel engageable over the said throat portion to provide a guard extension for the said wires entering between the said rings, a contact at the inner terminal of each wire, said terminal projecting thru the slot to provide attaching means exteriorly of the said rings, a coating of sealing wax or other water-proofing substance enveloping the said rings and the said guard extension, and

means positively connecting the said rings, one to the other and to the guard extension.

6. A protecting device for the timer wire assembly of an automobile comprising, a pair of superposed annular disks of insulating material, one of said disks having circumferentially spaced contact members seated therein projecting laterally therethrough and adapted to fit over the timer contacts, spaced wires extending circumferentially between said disks and connected to said contact members at one end and having their other ends projecting at adjacent points at the edges of said disks, a member enclosing the said projecting ends of said wires and a cover for said disks extending from said member around the disks and adapted to hold the disks in position.

7. The combination with a flexible conduit having a plurality of insulated timer wires therein, of a flat member having diverging sides connected to said conduit, said wires diverging substantially in one plane in said member, a flat annular casing secured to said member, a thin rigid member in said casing having grooves in which said wires are disposed substantially in one plane and extending to points ninety degrees apart therein, means for holding said wires in said last mentioned member, a contact member comprising flat plates bent substantially at right angles secured to the terminal of each wire and having one portion secured in said flat casing and another portion projecting therefrom and substantially at right angles to the plane thereof, said projecting portion being provided with a slot adapted to fit over the terminal post of the timer casing.

In testimony whereof I affix my signature.

WILLIAM J. PETERSON.
